UNITED STATES PATENT OFFICE.

JAMES A. MCPHERSON, OF HAMILTON, CANADA.

HOCKEY-BOOT.

No. 811,816.

Specification of Letters Patent.

Patented Jan. 30, 1906.

Application filed March 28, 1904. Serial No. 200,497.

To all whom it may concern.

Be it known that I, JAMES ADOLPHUS MCPHERSON, a subject of the King of Great Britain, residing at Hamilton, in the county 5 of Wentworth, Province of Ontario, Dominion of Canada, have invented a new and useful Improvement in Hockey-Boots, of which the following is a specification.

My invention relates to an improvement 10 in ankle-supports for boots and shoes, and is particularly designed for use in connection with hockey-boots or other foot-gear worn in athletic exercises wherein a support for the ankles of the wearer is desirable, although 15 the invention is of course applicable to any boot or shoe.

The object of my invention is to afford a firm support for the ankles of the wearer in combination with the boot or shoe and one 20 which can be fastened or unfastened with ease and facility either before or after the boot or shoe to which it is applied and in combination with which it is used has been buttoned or laced.

My invention therefore consists in the combination, with a boot or shoe, of an ankle-support comprising a flexible piece of material secured within and along the rear or back seam of the upper of the boot or shoe, so that 25 the sides of the support will form two flaps, one of which is provided with an extension and with a strap or other suitable fastening device which passes through a slot cut in the upper and is secured by means of a buckle or 30 similar device secured to and exteriorly of the upper, the object of this fastening being to avoid the objection of having to lace the ankle-support prior to lacing the shoe, which is both tedious and troublesome.

My invention further consists in certain 40 novel details of construction and combinations of parts, such as will be more fully described hereinafter and particularly pointed out in the claims.

In the accompanying drawings, Figure 1 45 is a perspective view of a shoe with which my invention is combined. Fig. 2 is a view in front elevation showing the shoe unlaced, and Fig. 3 is a transverse sectional view 50 across the upper.

In the drawings, A indicates the shoe, provided with the usual vamp 1, to which the tongue 2 is secured in the usual manner, (not shown,) and the upper 3 3', slit along its longitudinal median line and provided with the eyelets 4 4 for the reception of a lacing.

Although I have shown my invention as applied to a laced shoe, it is perfectly obvious that the same may be used in connection with a button-shoe as well.

60

Received within the upper is the ankle-support B, comprising a flexible piece of material—as canvas, for instance—conforming in general shape to the shape of the upper and stitched or otherwise secured to the back 65 seam 5 of the upper, a line of stitching 6 securing the sides of the ankle-support to the sides of the upper for firmly retaining it in place, whereby the flaps 7 7 are left free of the upper and in position to closely embrace 70 the instep of the wearer's foot. The ankle-support may be made of a single piece or of two pieces stitched together at the back seam.

The free ends of the flaps 7 7 may be cut 75 away to conform in general shape with the curvature of the eyeleted portion of the upper, and one of the flaps on the side 3' of the upper is somewhat longer than the other, although this is not necessary, the longer 80 flap having stitched or otherwise formed or secured thereto an extension 8, which passes over the median line of the instep of the wearer and overlaps the opposite flap, the extension 8 being provided with a strap 9, 85 adapted to pass through a slot 10, formed in the upper 3 in the rear of the eyeleted portion thereof and approximately parallel therewith.

Exteriorly of the side of the upper 3 and 90 rearwardly of the slot 10 is located the buckle 11, secured to the upper by means of a tab 12, the strap adapted to engage the buckle to close and retain the ankle-support firmly around the ankle of the wearer, the tightening 95 of the ankle-support also serving to take in any slack in the upper itself and cause it to embrace and fit the ankle of the wearer perfectly.

It will be noted that the stitching 6 is located beneath the ankle of the wearer, so that the flaps and the upper are left free to be drawn as tightly as desired thereover, and this arrangement, while affording a brace and strengthening the ankle, does not impede its 100 action in the slightest.

The buckle 11 is preferably located on that side of the upper which is outermost; but this is not essential.

The operation of my invention is obvious. 110 The wearer places the shoe on the foot and, inserting the strap through the slot, draws

the support as tightly about the ankle as is desired. The strap is then fastened to the buckle and the shoe laced or buttoned in the usual manner. The removal of the shoe may also be effected with ease and facility.

From the foregoing it is evident that many changes might be made in the form and arrangement of the various parts described without departing from the spirit and scope 10 of my invention, and hence I do not wish to limit myself to the exact construction herein set forth; but,

Having thus fully disclosed my invention, what I claim as new, and desire to secure by 15 Letters Patent, is—

1. The combination with a boot or shoe provided with an upper, of an ankle-support comprising a flexible material secured adjacent the rear seam of the boot, and consisting 20 of flaps movable relative to the upper, one side of the upper provided with a slot, a fastening device located exteriorly of the upper and adjacent the slot, and a connection carried by the flap opposite the slotted upper,

the connection adapted to pass through the 25 slot in the upper and be engaged by the fastening device.

2. The combination with a boot or shoe provided with an upper slit longitudinally of its length and having fastening means located on either side the slit, of an ankle-support secured within the upper adjacent the rear seam thereof, the ankle-support provided with flaps movable relative to the upper, the ankle-support conforming approximately in shape to the shape of the upper, one of the flaps adapted to overlap the opposite flap, a strap carried by the first-named flap, that side of the upper opposite the strap-carrying flap being provided with a slot, a 30 fastening device located adjacent the slot and exteriorly of the upper the strap adapted to pass through the slot and be engaged by the fastening device.

JAS. A. McPHERSON.
